APPARATUS FOR WORKING METAL

Alva W. Woodward, Kent, Ohio, assignor to
Wingfoot Corporation, Wilmington, Del., a
corporation of Delaware

Application October 26, 1934, Serial No. 750,080

9 Claims. (Cl. 29—33)

This invention relates to mechanism for working metal as by pressing or rolling, and more particularly is concerned with the manufacture of metallic rims for automobile or like use.

5 In the past rims for pneumatic tires and the like have been made up from suitable flat stock which is either hot or cold rolled into a flat strip which is substantially of the cross-sectional contour of the finished rim. However, some difficulty was experienced in properly rolling the rim 10 gutter and the overhanging tire supporting flange due to the angle and curvature of these parts, so that it has been proposed (reference may be had to my Patent No. 1,934,650 issued November 7, 15 1933) to roll the rim section with a bent or angle base which permits the rolls to more accurately form the overhanging and curved portions of the section. The angle base sections are then rolled or pressed flat and the manufacture of the rim 20 completed by the usual formation of the section into a circle with the standard welding and splitting operations following.

Some difficulty has likewise been encountered in properly positioning the rim sections during 25 the base flattening operation, although my former Patent No. 1,934,650 referred to above discloses one manner of aligning the rim section during the base flattening operation.

My present invention has for an object the provision of an improved method and apparatus for 30 positioning and aligning rim sections or the like during pressing or rolling operations, such as for example that of flattening the angle base of a rim during its manufacture.

35 Another object of the present invention is to provide resilient means for normally holding a metal portion during a pressing or rolling operation so that the portion is properly positioned during the entire operation.

40 Another object of the invention is to provide aligning and positioning means of the character described which are simple, efficient and commercially practical.

Another object of the invention is to provide an 45 improved method for handling and working metal such as rim sections.

The foregoing and other objects of the invention are achieved by the method and apparatus hereafter minutely described, the said apparatus 50 being illustrated in the attached drawing, wherein:

Fig. 1 is a plan view of one embodiment of the invention adapted for pressing metal sections;

Fig. 2 is a side elevation of the apparatus seen 55 in Fig. 1;

Fig. 3 is a cross-sectional view taken on the line III—III of Fig. 2;

Fig. 4 is a side elevation of a second embodiment of the invention illustrating the principles thereof as applied to metal rolling equipment; 5

Fig. 5 is a cross-sectional view, on a somewhat larger scale, on line V—V of Fig. 4.

It will be appreciated that the features of the invention are applicable to various types of metal 10 forming and handling equipment. However, in accordance with the patent statutes, certain best known forms of the invention have been selected for complete illustration and description. Inasmuch as the invention is particularly concerned 15 with the manufacture and treatment of angle base rim sections prior to a circle rolling operation, these forms of the invention have been selected.

Referring now to Figs. 1, 2 and 3, the numeral 10 indicates generally a bed which is mounted in 20 any suitable manner (by means not shown), so that a reciprocating platen or die head shown generally at 12 is adapted for movement toward and from the bed 10. The bed 10 is formed with a longitudinal groove or channel 14 which is 25 adapted to receive the rim section R which is flattened during the pressing operation from the full line position seen in Fig. 3 to the dotted line position of the same figure. The bed 10 may be provided with a reinforced anvil bar 16 adjacent the 30 channel 14 which will function to insure the proper formation of the desired rim section during the flattening operation. The exact details of the bed 10 and plunger 12 are not important per 35 se, other than to assist in the desired shaping operation.

The present invention is primarily concerned with providing means for resiliently positioning the rim section R during the base flattening operation, and these means may take the form of a 40 resiliently mounted plunger 20 which includes a shaft 22 and a compression spring 24, the whole being slidably carried in a circular recess 26 formed in the bed 10 and in an auxiliary block 28 secured to the bed as by cap screws 30. The 45 outward position of the plunger 20 can be made adjustable, as by providing adjusting and lock nuts 32 on the end of the shaft 22 which is, of course, appropriately threaded. The plunger 20 is preferably formed with a lug or boss 33 to increase its overall height thereby preventing the rim if warped from slipping over the end of the plunger 20. A slot may be cut in the bed 10 and block 28 to permit movement of the lug 33.

A plurality of the resilient plungers 20 are pro- 55

vided throughout the length of the bed 10, although two of these plungers are ordinarily sufficient to properly align and position the rim section R during the pressing operation.

5 It is believed that the operation of the apparatus will be apparent from the foregoing description. However, the operation briefly comprises first, adjusting the plungers 20 so that the rim section will be held with the gutter portion 10 thereof slightly spaced from the side of the channel 14 so that during the downward movement of the platen 12 the plungers 20 will yield against the action of compression springs 24 to permit the gutter portion of the rim to finally completely 15 fill the channel 14. In this manner the resilient plungers 20 serve to hold the rim section R resiliently in the desired alignment with the channel 14 and bed 10 as the platen 12 descends in the flattening operation. Sliding movement of the 20 edges of the rim section R on the bed 10 will thus be distributed between both sides rather than being all on one side only. Likewise, due to the 25 resilient nature of the plungers 20 they will not affect the true pressing operation of the platen 12 and bed 10 so that rim sections of the desired characteristics can be quickly and uniformly produced.

Figs. 4 and 5 of the drawing illustrate the application of the principles of the invention to rolling equipment for flattening an angle base rim section. In this embodiment of the invention the rim section has been indicated by the letter S and the same is adapted to be passed through a plurality of cooperating rolls indicated at 40 and 30 42, 44 and 46, 48 and 50, 52 and 54, 56 and 58. As will be evident from Fig. 4, the rolls are placed in alignment and are gradually positioned closer together so that in passing the metal section S through the rolls the angle base thereof will be 35 gradually and smoothly flattened to the desired cross-sectional dimensions and shape. The invention contemplates employing only one set of cooperating rolls and gradually moving the axes of these rolls together to achieve the same flattening 40 operation. The exact details of the construction and relation of these rolls does not constitute the paramount feature of my invention which is more directly concerned with providing means for resiliently holding and aligning the metal sections 45 as they pass through the rolls. Means for achieving this result will now be described.

Fig. 5 of the drawing is illustrative of one best known form of my invention for positioning the metal rim section S during the rolling operation, 50 and these means have been illustrated in conjunction with rolls 40 and 42 seen in Fig. 4 although it will be understood that the positioning means may be incorporated with any or all of the pairs of rolls. Roll 40 is provided with the usual periphery adapted to shape the rim section to give the proper angle between the gutter and base of the rim section, but, in addition, is provided with a spring-positioned sleeve 64 having a radially extending flange 66 which is adapted to contact 55 with the gutter portion of the rim section S. The sleeve 64 may be held in place by a collar 68 which is adjustably secured in any suitable manner to the roll 40, as by providing a threaded connection 60 thereto. The collar 68 may be formed 65 with an axially directed guiding flange 72, which surrounds and helps to guide the sleeve 64 as well as functioning as a stop for the movements of the sleeve. A compression spring 74 is received 70 between the flanges 66 and 72 and functions to normally hold the sleeve 64 and its integral guide 75

flange 66 over in a position to properly align the rim section S with the roll 40.

The roll 40 may be provided with radially directed and circumferentially spaced parts which partially define the gutter shaping area of the 5 roll. If this is done the guide flange 66 of the sleeve 64 is formed with axially extending portions which pass between the radially directed parts of the roll 40 so that the rim section S is still contacted by the flange 66 to properly position 10 the same. This construction is not preferred, however, inasmuch as the projecting corners which necessarily result do not readily adapt themselves to rolling operations. When the flange 66 is made full around the roll, the collar 15 68 is preferably adjusted so that it acts as a stop for the cushioning movement of the sleeve 64 and its integral flange 66, thereby insuring a proper formation of the gutter portion of the rim section S. 20

In the operation of the positioning means with the rolling equipment, the gradual flattening of the rim section S will push the aligning sleeve 64 in its flange 66 gradually back against the action of the compression spring 74 until the base portion 25 of the rim has been completely flattened.

By the mechanism of the present invention, centering or aligning means are provided for accurately positioning metal rim sections during pressing or rolling operations, thereby insuring 30 the formation of sections in which the gutter portion is of the proper dimensions and which has the exact angularity desired with respect to the base section of the rim. The sliding movement on the sides of the angle base rim section during the 35 flattening operation is so distributed as to avoid putting all sliding stresses on only one side, which may possibly damage the rim. Wear on the rolls or platen and bed is likewise properly distributed. The improved apparatus eliminates 40 any necessity for hand positioning with its correlated dangers and production inefficiency is elevated.

While the invention has been particularly described for use with rim handling apparatus, it 45 will be appreciated that the principles thereof can be adapted to other uses requiring similar operations and, accordingly, the invention is not limited to the specific examples thereof illustrated and described in detail, but is defined by 50 the appended claims.

What I claim is:

1. In apparatus for flattening angle base rim sections, the combination of a bed for receiving the section, a platen head adapted for reciprocating movement above the bed, and means for resiliently positioning the section on the bed during the flattening operation, said means including a plurality of spring held pins which contact with the rim section in a direction to yieldingly oppose 55 the flattening movement of the rim edge but which will yield to a position to permit the rim to be completely shaped.

2. In apparatus for flattening angle base rim sections, the combination of a bed for receiving the section, a platen head adapted for reciprocating movement above the bed, and means for resiliently positioning the section on the bed during the flattening operation.

3. In apparatus for flattening angle base rim sections, the combination of a bed for receiving the section, a platen head adapted for reciprocating movement above the bed, and means for resiliently positioning the section on the bed during the flattening operation, said means includ- 70 75

ing a plurality of spring held pins which contact with the rim section.

4. In apparatus for working metal sections, the combination of a bed for receiving the section, a platen head adapted for reciprocating movement above the bed, and means for resiliently positioning the section on the bed during the metal working operation, said means including a plurality of spring held pins which contact with the section in a direction to yieldingly oppose the flattening movement of the section edge but which will yield to a position to permit the section to be completely shaped.

5. In apparatus for flattening angle base rim sections, the combination with a bed having two bed portions at an angle to each other, a platen head having a portion facing said first two bed portions but at a greater angle to one of said portions than the other, and yielding means associated with the bed portion at the greater angle for engaging the adjacent edge of a rim section placed on said portions, whereby when said platen engages said rim section to straighten same, said yieldable means will yield in the direction in which said edge moves during the rim straightening operation, said yielding means acting also as a positioning means for positioning the rim section on said bed portions initially.

6. In an apparatus for flattening angle base rim sections, the combination with one forming member having at least two rim section engaging portions at an angle to each other, a second forming member having a rim section engaging face opposed to said two rim section engaging portions, but at a greater angle to one of said portions than the other, and yielding means associated with said portion which is at the greater angle to said face for engaging the adjacent edge of a rim section placed between said forming members, whereby when said forming members engage said rim section to straighten same, said yielding means will yield in the direction in which said edge moves during the rim straightening operation, said yielding means acting also as a positioning means for positioning the rim section on said first forming member initially.

7. In an apparatus for flattening angle base rim sections, the combination with one forming member having at least two rim section engaging portions at an angle to each other, a second forming member having a rim section engaging face opposed to said two rim section engaging portions, but at a greater angle to one of said portions than the other, and yielding means associated with said portion which is at the greater

angle to said face for engaging the adjacent edge of a rim section placed between said forming members, whereby when said forming members engage said rim section to straighten same, said yielding means will yield in the direction in which said edge moves during the rim straightening operation, acting also as a positioning means for positioning the rim section on said first forming member initially, said forming members comprising a pair of rollers arranged in opposed relation. 10

8. In an apparatus for flattening angle base rim sections, the combination with one forming member having at least two rim section engaging portions at an angle to each other, a second forming member having a rim section engaging face opposed to said two rim section engaging portions but at a greater angle to one of said portions than the other, and yielding means associated with said portion which is at the greater angle to said face for engaging the adjacent edge 15 of a rim section placed between said forming members, whereby when said forming members engage said rim section to straighten same, said yielding means will yield in the direction in which said edge moves during the rim straightening operation, acting also as a positioning means for positioning the rim section on said first forming member initially, the edge of said rim section opposite to that as engaged by said yielding means 20 being unrestricted as to its lateral movement except for frictional forces.

9. In an apparatus for flattening angle base rim sections, the combination with one forming member having at least two rim section engaging portions at an angle to each other, a second forming member having a rim section engaging face opposed to said two rim section engaging portions, but at a greater angle to one of said portions than the other, and yielding means associated with said portion which is at the greater 35 angle to said face for engaging the adjacent edge of a rim section placed between said forming members, whereby when said forming members engage said rim section to straighten same, said yielding means will yield in the direction in which 40 said edge moves during the rim straightening operation, acting also as a positioning means for positioning the rim section on said first forming member initially, the edge of said rim section opposite to that as engaged by said yielding means 45 being unrestricted as to its lateral movement, except for frictional forces, and said forming members comprising a pair of rollers.
